DESIGN FOR A COMBINED STAND AND PERFUME BOTTLES

Arthur R. Botham, New York, N. Y., assignor to Coty, Inc., a corporation of Delaware

Application February 6, 1943, Serial No. 109,492

Term of patent 7 years

To all whom it may concern:

Be it known that I, Arthur R. Botham, a citizen of the United States, residing in the city, county, and State of New York, have invented a new, original, and ornamental Design for a Combined Stand and Perfume Bottles, of which the following is a specification, reference being had to the accompanying drawing, forming a part thereof.

Fig. 1 is a front elevational view of a combined stand and perfume bottles showing my new design;

Fig. 2 is a top plan view thereof.

The dominant features of my design reside in the portions shown in full lines.

I claim:

The ornamental design for a combined stand and perfume bottles, substantially as shown and described.

ARTHUR R. BOTHAM.
